UNITED STATES PATENT OFFICE.

PAUL GSCHWEND, OF CANTON, OHIO, ASSIGNOR TO ELBEL & CO., OF SAME PLACE.

DESIGN FOR A CHECKREIN-HOOK.

SPECIFICATION forming part of Design No. 19,568, dated January 7, 1890.

Application filed November 29, 1889. Serial No. 332,033. Term of patent 14 years.

To all whom it may concern:

Be it known that I, PAUL GSCHWEND, a citizen of the United States, residing at Canton, in the county of Stark and State of Ohio, have invented a new and original Design for Checkrein-Hooks, of which the following is a specification.

The invention relates to a new and original design for checkrein-hooks.

10 In the drawings, Figure 1 is a perspective view of a checkrein-hook showing my new design. Fig. 2 is a side elevation.

15 The essential feature of the design is the rectangular loop having an opening near its lower rear end and being extended rearward at the opening.

A designates a loop which is rectangular in cross-section and has an opening *a* at its rear side, near the bottom thereof. The loop

20 A has its bottom *a'* extended rearwardly beyond the opening *a*, and is provided with

a stem *B*, and the said loop *A* has a horizontal arm *C*, that extends rearward from the back *a²* and projects beyond the bottom *a'*.

What I claim is—

25 The design for checkrein - hooks herein shown and described, the same consisting of the loop *A*, rectangular in cross-section, and provided at its lower rear side with an opening *a*, and having its bottom *a'* extending 30 beyond the opening and its back *a²* provided with the rearward-extending arm *C*, projecting beyond the bottom *a'*, substantially as shown and described.

In testimony that I claim the foregoing as 35 my own I have hereto affixed my signature in presence of two witnesses.

PAUL GSCHWEND.
